VIBRATORY COIL

Bennett M. Leece, Cleveland, Ohio, assignor to
The Leece-Neville Company, Cleveland, Ohio, a
corporation of Ohio

Application May 9, 1933, Serial No. 670,985

4 Claims. (Cl. 200—90)

This invention relates to a vibrating coil for voltage regulators and the like, and has for one of its objects to provide a coil which is inexpensive to produce and wherein the parts are compactly arranged and readily assembled into a vibrating coil which is effective as well as economical in construction, particularly for quantity production.

A further object of the invention is to provide a construction having provision for automatic compensation for changes in the resistance of the winding or windings of the coil due to heating thereof without the necessity of a special thermally responsive resistance element. In brief, it is one of the objects to provide a vibrating coil wherein the desired voltage output of the generator with which the coil is used is maintained substantially constant without requiring the use of expensive metals or materials, such as a material having a negative temperature coefficient, to prevent a change in the ampere turns of the winding or windings of the coil due to change in temperature.

A still further object is to provide an improved and simplified form of vibrating armature, preferably in the form of an inexpensive stamping which lends itself readily to quick assembly in the built-up structure of the coil without requiring a pivot, and, further, to form this vibrating armature in a manner such that it has a high rate of vibration when the coil is in use.

In the accompanying sheet of drawing, Fig. 1 is a longitudinal sectional view through a vibrating coil embodying the invention in its preferred form; Fig. 2 is a top plan view; Fig. 3 is a section substantially along the line 3—3 of Fig. 1, (Figs. 1, 2 and 3 showing the coil on an enlarged scale for the sake of clearness); and Fig. 4 is a diagrammatic view illustrating conventionally one system with which the coil may be used to advantage.

My improved vibrating coil is not confined to any particular system or to any particular number of windings which are housed in the metal shell of the device. It may contain a single winding, two windings, or even more.

In Fig. 4 I have shown a vibrating coil having two windings with circuit connections similar to those disclosed in my prior Patent No. 1,633,671. With the system illustrated in Fig. 4, which finds its greatest use on automobiles to supply current to the load at a substantially constant voltage regardless of speed changes, 10 represents the armature of the generator, the brushes of which are connected to the load circuit wherein the load

consists of a battery 11 and lamps 12. The generator has a field winding 13 one terminal of which is connected to one of the brushes of the generator and the other to the stationary contact 14 of the vibrator. The movable contact 15 is carried by a vibrating armature 16 which is usually pivotally supported on a frame or housing 17 but which, according to the present invention, has a novel form and mounting to be described, the housing having a core 18 surrounded by one or more windings 19, in this instance two windings designated 19a and 19b in Fig. 4, which windings are sometimes termed the primary and the secondary. The stationary contact 14 is connected to one terminal of the winding 19b while its other terminal is connected to one terminal of the winding 19a whose other terminal is grounded on the frame or housing 17. At the point where the two windings are connected, connection is made by means of a conductor 20 to one brush of the generator, the other brush being connected by a conductor 21 to the frame or housing 17. Between this conductor 21 and the conductor 22 which connects the field winding 13 to the stationary contact 14 is a resistance 23 which is cut into the field circuit when the contacts are separated by the magnetic pull and which is short-circuited when the contacts are in engagement, the armature being moved away from the core so as to cause the movable contact 15 to engage the contact 14 by a spring 24. It is to be understood that while I have shown in some detail one generating and voltage regulating system, my vibrating coil is not necessarily confined to a system such as illustrated, particularly as to the number of windings on the core 18.

It might be here stated that the present invention resides in the assembly of the different parts composing the vibrator and also in the construction and manner of supporting or mounting the vibrating armature 16 and in the location or relation of the spring 24 with respect to the core 18.

In the description of the details of construction of these parts, the reference characters as applied to Fig. 4 and others will be utilized.

Referring first to Fig. 1, it will be seen that the housing 17 includes a cylindrical shell 17a the bottom of which is closed by a disk 17b which is fitted into the shell and rests against a shoulder 17c near the bottom thereof. The opposite end of the shell is threaded interiorly and there is fitted into the top an externally threaded disk 17d constituting a nut by which the parts hereinafter referred to are clamped solidly against

each other and down onto the bottom disk or base 17b. Extending upwardly from the bottom 17b of the shell 17 centrally thereof is the core 18, and surrounding the core are the winding or windings 19, the same being shown conventionally inasmuch as, as previously pointed out, the number of windings may be varied from one to two or more. For convenience, the same will be referred to as the winding 19. It may be stated, however, that if two windings are employed, such as those illustrated in Fig. 4 at 19a and 19b, the primary winding 19a will be wound around the core and the secondary winding 19b on the primary. It will be understood, of course, that these will be preformed coils which, as a unit, can be slipped into the shell around the core. I may also wind about the secondary the resistance 23 of Fig. 4, a wire resistance being preferably utilized. The two windings and the resistance, if the same are provided in the housing, fill the space between the core and the cylindrical wall of the shell.

Between the winding 19 and the bottom disk 17b is suitable insulation 25, and at the top of the winding there is similar insulation 26. Surrounding the upper or free end of the core and engaging the insulation 26 is a metal disk 27 which fits closely in the shell 17a of the housing 17. It might be here stated that the shell 17a, the bottom disk 17b, and the core 18 are of course formed of magnetic material, such as steel, whereas the upper disk 27 is preferably formed of non-magnetic material, such as brass. The core may be supported on the lower disk or bottom closure 17b of the housing in any suitable way, but in this instance the lower end is reduced and is extended through a centrally disposed opening in the disk 17b and the lower end is peened over or upset to firmly secure it to the disk 17b. The disk 27 of non-magnetic material also has a centrally disposed opening which fits fairly closely over the free end of the core so that the disk serves to centralize the core in the sleeve or shell 12.

45 The vibrating armature, in this instance, is novelly constructed and mounted, the same consisting preferably of a ring-like stamping 16a with an inwardly extending vibratory arm 16b carrying on the upper side thereof the movable contact 15 which is arranged at the axis of the housing. The external diameter of the stamping 16a is such that it will fit closely in the shell 17a, and the annular or peripheral portion of the stamping is clamped between two rings 28 and 29, the latter being engaged by the clamping nut 17d. The armature stamping 16a and the rings 28 and 29 are preferably formed of steel. It is to be here noted that the following parts, insulating disk 25, winding 19, upper insulating disk 26, disk 27, ring 28, armature stamping 16a, and ring 29, are dropped successively into the housing and all parts are tightly clamped together by screwing down the nut 17d.

Fastened on top of the nut 17d by a pair of insulated screws 30 is a bridging member 31 (see Figs. 1 and 2) having at the center or axis of the housing an upstanding flange or boss 31a threaded on the interior and receiving an adjustable screw 32 which at its inner or lower end carries the stationary contact 14 which may be formed of any suitable material, such as tungsten. In this instance the tungsten is secured to a holder which is preferably made of brass in turn secured to the lower end of the screw. 70 Both the bridging member 31 and the screw car-

rying the stationary contact are preferably formed of magnetic material, such as steel. The screw 32 will be adjusted to properly position the stationary contact 14, after which it is secured in position by a lock nut 33.

Carried on the top face of the free end of the arm 16b of the armature stamping is the movable or vibratory contact 15 which, like the contact 14, may be formed of tungsten or other suitable material. This contact 14 is pressed into engagement with the lower face of the contact 15 when the winding is deenergized, as illustrated in Fig. 1, but, as is well understood in the art, when the vibrating coil is functioning, the armature is rapidly vibrated, moving the contacts into and out of engagement and cutting the resistance 23 into and out of the field circuit.

One of the important features of the invention resides in the arrangement of the spring 24 (which acts on the vibrating arm 16b of the armature to restore the contacts into engagement immediately after they have been separated by the magnetic pull of winding 19) not only to facilitate assembly and to obtain a high degree of compactness, but also for another purpose to be mentioned presently. This spring 24 is located in a bore 34 extending centrally of the core 18 preferably throughout its length. This spring, which is a coil spring of considerable length, at its upper end bears against the under side of the arm of the vibrator at the axis of the coil and at its lower end bears against an adjustable abutment adapted to be adjusted to vary the compression of the spring. For this purpose, the lower part of the bore 34 is enlarged and is internally threaded and receives an adjustable screw 35 a portion of which projects out through the bottom disk 17b of the coil, a lock nut 36 being provided to lock the screw in any position to which it may be adjusted. The lower end of the spring may bear directly against the upper end of screw 35, but in order to avoid the use of an unnecessarily long screw, I may provide between the lower end of the spring and the upper end of the screw a plug 37, which may be of brass, of suitable length to serve as the direct abutment for the spring.

A very important functional advantage is attained by this arrangement in the way of an automatic adjustment or compensation during the operation of the coil, for, when the winding heats up, due to the passage of current therethrough or from the heat of the engine, or otherwise, the resistance of the winding increases and its ampere turns correspondingly decrease, but with the present arrangement of the core and spring, this is automatically compensated for because the core expands lengthwise under the action of the heat and decreases the magnetic reluctance of the air gap and therefore increases the magnetic pull on the armature, while at the same time the action of the heat on the spring causes the individual convolutions to expand and the diameter to increase, and this in turn decreases the effective length of the spring. Both of these results tend to increase the action of the winding on the armature in direct proportion to what would otherwise be a decreased action due to the increased resistance of the winding and the consequent decrease in current passing through it. Thus the rate of vibration of the armature is maintained constant and the voltage does not build up, as would otherwise be the case, and I am enabled to accomplish this result without employing a special and usually expensive mate- 75

rial in the circuit of the winding, such as one having a negative temperature coefficient, to neutralize or compensate for the increased resistance of the winding on heating.

5 The electrical connections to the parts inside of the housing may be made through one or more of the screws 30 or otherwise, as may be found most convenient.

It will be seen from the above that the advantages or objects stated at the beginning of the specification are attained in a very effective manner. The compactness and ease of assembly by reason of the fact that the parts can easily be slipped into the housing and secured in place by simply tightening down the nut 17d, are obvious from the drawing, as is also the ease of adjustment of the contacts accomplished by adjustment of the screws 32 and 35 at opposite ends of the housing. These features contribute greatly to the low cost of production of the coil, as does also the armature which requires no pivot, and the fact that the arrangement of the spring within the bore of the core, as herein illustrated eliminates the necessity of a special compensating resistance or conductor in the winding circuit as has frequently been required heretofore.

While I have shown the preferred construction, I do not desire to be confined to the precise details shown, as changes may be made without departing from the spirit and scope of the invention, as defined in the appended claims.

Having thus described my invention, I claim:

1. A vibrating coil comprising a cylindrical shell having an end disk adjacent the lower end and a centrally disposed core supported by and extending from the disk, a winding surrounding the core, an armature having an annular peripheral portion, annular armature supporting members fitted within said shell and engaging opposite sides of said peripheral portion of the armature, and a closure for the upper part of the shell in the form of a nut screwed into the end of the shell for clamping cooperation with said end disk to hold the parts in assembled relationship.

45 2. A vibratory coil having a housing including a cylindrical shell, a bottom closure therefor in the form of a disk engaging the housing near one end and carrying a core extending centrally of the shell, a winding surrounding the core, a non-magnetic centralizing disk fitted into the shell

and having an opening for the free end of the core, a disk armature having an annular portion fitted inside the shell and a vibratory arm portion extending into cooperating relation with said free end of the core, and a clamping nut 5 screwed down into the other end of the shell and forming a closure for said other end.

3. A vibratory coil having a housing comprising a cylindrical shell, a bottom disk seated at one end thereof and having a core extending 10 axially of the shell, a winding surrounding the shell, a centralizing disk of non-magnetic material fitted into the shell and surrounding the core adjacent its free end, a pair of annular members fitted into the shell above said centralizing disk, 15 an armature comprising an annular part fitted into the shell between said annular members and a vibratory part carried by the annular part, a contact on said vibratory part, and a nut screwed into the upper part of the shell for clamping 20 together and holding in assembled relationship the above mentioned parts which are fitted into the shell, said nut carrying an adjustable centrally disposed contact for cooperation with the contact on said vibratory part. 25

4. In a vibratory electro-magnetic device the combination of an elongated housing having internal abutment means at one end thereof, a magnet spool comprising a core and end disks and a winding around the core and between the 30 disks, said magnet spool being disposed in the housing with its core extending axially thereof and with one disk engaging said abutment means and forming an end closure for the housing and the other end disk spaced inwardly from the 35 other end of the housing, a closure having threaded connection with said other end of the housing and spaced from said other end disk to provide a chamber therebetween, a disk-like armature in said chamber and having a vibratory 40 arm portion in proximity to an end of said core, a pair of cooperating contacts in said chamber one being carried on said arm portion and the other being carried on said closure, and supporting means in said chamber and fitted into the 45 housing for engaging edge portions of said armature, said closure and said abutment means cooperating to clamp said spool and said armature supporting means therebetween.

BENNETT M. LEECE. 50
